UNITED STATES PATENT OFFICE

ALPHEUS W. ALTORFER, OF PEORIA, ILLINOIS, ASSIGNOR TO ALTORFER BROS. COMPANY, OF EAST PEORIA, ILLINOIS, A CORPORATION OF ILLINOIS

DESIGN FOR A COMBINED CASING FOR A WASHING MACHINE AND CENTRIFUGAL DRIER

Application filed July 2, 1931. Serial No. 40,403. Term of patent 14 years.

To all whom it may concern:

Be it known that I, ALPHEUS W. ALTORFER, a citizen of the United States, residing at Peoria, in the county of Peoria and State of Illinois, have invented a new, original, and ornamental Design for a Combined Casing for a Washing Machine and Centrifugal Drier, of which the following is a specification, reference being had to the accompanying drawings, forming a part thereof.

Figure 1 is a side perspective view of a combined casing for a washing machine and centrifugal drier, showing my new design.

Figure 2 is an end perspective view of the same.

I claim:

The ornamental design for a combined casing for a washing machine and centrifugal drier, substantially as shown.

ALPHEUS W. ALTORFER.
